UNITED STATES PATENT OFFICE.

CARL HOLSTEIN, OF CHICAGO, ILLINOIS.

DESIGN FOR A CHAIR.

SPECIFICATION forming part of Design No. 25,184, dated February 18, 1896.

Application filed December 23, 1895. Serial No. 573,164. Term of patent 3¹ years.

To all whom it may concern:

Be it known that I, CARL HOLSTEIN, a citizen of the United States, residing at Chicago, Cook county, State of Illinois, have invented and produced a new and original Design for Chairs, of which the following is a specification, reference being had to the accompanying drawing, forming a part of this specification.

- 1. The drawing shows a perspective view of a rocking-chair illustrating my design.
- 2. The leading feature of my design is embodied in the back of the chair and more especially in the outline thereof. The back is shown as extending from side to side, the center being shown as formed with an ornamental scrollwork cut therein. The outer edges of the top, bottom and sides of the back are cut upon the curved lines shown, the upper corners of the back being rounded, as shown. At the top and bottom and beneath the open-work of the center ornamental molding of the

design shown is applied to the front of the back, although this is not essential.

The arms of the chair are shown as projecting from the face of the back, these arms being of the general configuration shown, and from these arms extend downwardly the legs, the legs above and below the seat of the chair being curved and of the configuration shown, while that portion of the legs adjacent to the chair-seat is straight.

The seat of the chair is shown as of the so-called "saddle-shaped" outline.

The rear legs and rockers are shown as of the ordinary type.

What I claim as of my invention, and desire to secure by Letters Patent, is—

The design for a chair, substantially as shown and described.

CARL HOLSTEIN.
